D. F. DYKE

RAIL FASTENER

Filed May 19, 1919

UNITED STATES PATENT OFFICE.

DARRELL F. DYKE, OF CHICAGO, ILLINOIS, ASSIGNOR TO THE SENG COMPANY, OF CHICAGO, ILLINOIS, A CORPORATION OF ILLINOIS.

RAIL FASTENER.

Application filed May 19, 1919. Serial No. 293,270.

To all whom it may concern:

Be it known that I, DARRELL F. DYKE, a citizen of the United States, residing at Chicago, in the county of Cook and State of Illinois, have invented certain new and useful Improvements in a Rail Fastener, of which the following is a specification.

This invention relates to a device for fastening the end of a rail to a supporting post, but is more particularly designed and intended as a bed rail fastener, although of course, it may have a more general use wherever applicable.

The principal object of the invention is to provide means for operating a hook at the end of a rail for drawing it up tightly in connection with a supporting post.

In the accompanying drawing Fig. 1 is a side view of a device constructed in accordance with the principles of this invention; Fig. 2 is a top or plan view thereof; and Fig. 3 illustrates a wedge acting modification.

Bed rail fastenings are common in which there is a fixed hook projecting from the end of the rail and adapted to be hooked over a supporting pin in a slot or a bed post or support. The present invention differs from constructions of this kind by providing a loose hook with an operating member for drawing it tightly against a supporting pin.

Referring more particularly to the drawing, a rail 1 preferably of angle bar construction is provided with a plate 2 rigidly secured thereto by fastening means 3 and with the outer edge 4 of the plate 2 bent at right angles thereto and formed with a slot 5 extending parallel with the plate portion which is attached to the rail.

Extending through the slot 5 is a member 6 having a hook 7 at its outer end and with projections 8 along the upper edge which are spaced apart substantially the thickness of the plate 4 through which the member extends, and the projections are disposed one at each side of the plate so that the space between them forms a seat which bears against the upper end of the slot. A shoulder 9 is formed on the opposite side of the member 6 adjacent the inside edge of the hook 7 so that it substantially fits the slot 5 when the member 6 is in the position shown in Fig. 1. In order to insert or withdraw the member 6 from its engagement with the slot 5, the member 6 is drawn in-

wardly so that the shoulder 9 is free from engagement with the lower end of the slot, whereupon the projections 8 may be engaged or disengaged from the upper end of the slot and the member 6 moved accordingly. 60

An operating member disposed between the inner end of the hook member 6 and the side of the plate 2 as shown in Figs. 1 and 2 comprises a cam 10 with a handle 11, the cam portion of which is attached to the inner end of the member 6 by means of a bolt or rivet 12. This rivet 12 also extends through a slot 13 in the plate 2 and the rivet is commonly provided with a head 14 which is larger than the slot 13 so that when the parts are assembled the operating and hook members cannot become disengaged from the plate 2. The slot 13 is preferably curved about the upper edge of the slot 5 as a center, as the member 6 is oscillated about the projections 8 when the hook member is operated. 70

With this construction it is obvious that when the handle 11 is in its lowermost position as shown in Fig. 1, the highest portion of the cam engages the plate 4 between the slot 5 and the adjacent corner of the member 2 so that the hook member is drawn inwardly, and that when the handle member is raised, the lower portion of the cam will be brought into engagement, allowing the hook 85 to be released.

Approximately the same construction with the exception of the operating member is shown in Fig. 3 in which a wedging member 15 having an angularly disposed slot 16 is 90 slidably mounted upon the rivet 12 and by moving it downwardly the hook member 6 is drawn inwardly, and by moving it upwardly the hook member is released.

In both of these constructions the eccentricity of the cam and the inclination of the slot 16 is such that the operating member will hold the hook member in any position in which the operating member is set so that it may be tightened and left in any position 100 without danger of disengagement of the hook. Both of these constructions are commonly employed in connection with a post 17 having a pin 18 extending transversely of a slot 19 therein so that the hook 7 may be 105 inserted and engaged over the pin. The movement of the operating member draws the angular bearing portion 4 of the plate 2 tightly against the slotted side of the post by the engagement of the hook with the pin. 110

I claim:

1. In a bed rail fastener, an angular end plate attachable to a bed rail and having a slot in one portion thereof spaced from the other angular portion, a member disposed in the slot having a hook on the outer side of the plate, and means connecting the hook and the plate for operating the hook, said means comprising a lever having a cam operating surface and being pivotally connected to the hook and loosely pivoted in the plate.

2. In a bed rail fastener, a slotted bearing plate, a hooked attaching member disposed and movable in the slot, and having means at one side of the member for engaging the plate at the end of the slot, and means connected to the plate and member for moving the member about said end of the slot as an axis.

3. A bed rail fastener comprising a right angled plate one portion of which is attachable to a bed rail and the other portion of which is formed with a slot parallel with the first named portion, a member with a hook projecting through the slot and having means for engagement with the plate at the upper end of the slot to permit a pivoting movement of the member, and lever operated means between the member and the first mentioned portion of the plate engaging both the member and the plate for moving the member pivotally in the slot.

4. The combination with an end member angular in form having a slot in one portion parallel with and spaced from the other portion, a member having a hook extending through such slot with means for engaging the first mentioned member at one end of the slot to permit an oscillating movement thereof, a fastening device extending through the inner end of the hook member and through said other portion of the first mentioned member, the latter being formed with an enlarged perforation to permit the movement of the hook member, and means for moving the hook member to cause its oscillation.

5. In a bed rail fastener, a right angled end member having a slot in one portion parallel with the other portion thereof, a hook member extending through the slot with means at one side to engage one end of the slot and with a shoulder at the other side to prevent the disengagement of the said means, a fastening device extending through the rear end of the hook member and the adjacent angular portion of the member to permit the movement of the hook member in the slot, and means for imparting a limited movement to the hook member.

6. In a bed rail fastener, an angular end

member with a slot in one portion parallel with and spaced from the other portion, a hook member extending through and movable in the slot, means permitting a movement of the hook member about one end of the slot as an axis, and an operating member disposed between the hook member and the parallel side of the end member and connected to them both and comprising a cam shaped portion for engaging the slotted end member and moving the hook member in the slot.

7. In a bed rail fastener, a right angled end plate having one portion adapted to be attached to a bed rail with the other portion disposed at right angles thereto and having a vertical slot therein parallel with and spaced from the first mentioned portion, an attaching member extending through and movable in the slot having a hook at the outer end, projections at one side to engage the end plate at one end of the slot for permitting movement of the attaching member about this end of the slot as an axis, and with a shoulder at the opposite side of the attaching member to prevent the disengagement of the projections with the other end of the slot, a headed fastening member extending through the inner end of the attaching member and through the side of the end plate, the latter being provided with an opening to permit a limited axial movement of the attaching member, and an operating member mounted on the fastening member between the attaching member and the end plate having a handled extremity and a cam shaped portion which bears against the inner side of the end plate at the edge of said slot for drawing the attaching member inwardly to engage its hook with a supporting pin.

8. The combination of a bed rail and a support therefor comprising a slotted post with a pin extending transversely in the slot, and a bed rail fastener comprising a right angled plate one portion of which is fixed to the end of the rail and the other portion of which is formed with a slot and is adapted to abut the supporting post, a member extending through the slot of the plate and having a hook engageable with the supporting pin, means for loosely connecting the member in the slot and for causing it to have a pivotal movement about the upper end of the slot, and operating means including a cam surfaced member on the inner side of the plate for engaging the hook member and the inner face of the plate to draw the hook up tightly in engagement with the supporting pin.

DARRELL F. DYKE.
